CLAIM

The ornamental design for a pair of foot boards for four-wheeled motorcycle, as shown and described.

DESCRIPTION

FIG. 1 is a front, left side, perspective view of a pair of foot boards for four-wheeled motorcycle showing my new design;

FIG. 2 is a left side view thereof;

FIG. 3 is a right side view thereof;

FIG. 4 is a front view thereof;

FIG. 5 is a rear view thereof;

FIG. 6 is a top plan view thereof; and,

FIG. 7 is a bottom view thereof.

The left side foot board and right side foot board of the pair of foot boards for four-wheeled motorcycle are mirror images of each other.

The elements shown in broken lines form no part of the claimed design.
